UNITED STATES PATENT OFFICE.

GEORGE L. FORESTER, OF ASHEVILLE, NORTH CAROLINA.

SWITCH.

1,253,165.

Specification of Letters Patent. Patented Jan. 8, 1918.

Application filed January 30, 1917. Serial No. 145,487.

To all whom it may concern:

Be it known that I, GEORGE L. FORESTER, a citizen of the United States, residing at Asheville, in the county of Buncombe and 5 State of North Carolina, have invented new and useful Improvements in Switches, of which the following is a specification.

The present invention relates to improvements in means for bridging the gaps between the frog and the main and siding rails at a railway siding, whereby the wheels of the rolling stock will be afforded a continuous tread when traveling either upon the main or siding rails.

15 It is another object of the invention to provide switch rails for the frog at a railway siding and to provide actuating mechanism therefor that is designed to be operated when the switch rails between the main 20 rails and siding are thrown, whereby to fill the gap between the frog and at their side rails communicating with the frog.

It is a further object of the invention to provide switch rails for a frog that will be 25 effectively supported and which will be operated in timed relation with the operation of the main switch points and which further are provided with means to retain the same in proper alignment with the point of 30 the frog and to be effectively held in such alignment to support the wheels of the rolling stock and consequently overcome the shock and jar incident to the passage of the rolling stock between the frog and the main 35 or siding rails.

It is a still further object of the invention to produce a switch for a railway frog that can be readily associated with the ordinary construction of such devices, which 40 shall be simple and which shall be strong and effective in operation.

With the above and other objects in view the improvement resides in the construction, combination and arrangement of parts set 45 forth in the following specification and falling within the scope of the appended claims.

In the drawing:

Figure 1 is a plan view illustrating the application of the improvement.

50 Fig. 2 is a greatly enlarged plan view of the frog and a portion of the main and side rails arranged adjacent to the frog, illustrating the improvement, parts being broken away and parts being shown in section,

Fig. 3 is a side elevation of the improvement, and

Fig. 4 is a sectional view approximately on the line 4—4 of Fig. 1.

In the drawing, the numerals 1 designate the rails for the main line and 2 the rails for the siding. The frog is indicated by the numeral 3, and the switch rails or points by the numerals 4. The switch points are provided with the usual bridle rod 5 having an extension 6 which is pivotally secured to 60 one arm of a bell crank lever 7, suitable means (not shown) being employed for operating the bell crank lever to switch the switch points 4 to close either the main line or the siding.

70 The second arm of the bell crank lever 7 has pivotally connected thereto a longitudinally extending rod 8 which in turn is connected with one of the arms of a second bell crank lever 9 that is disposed a suitable distance to one side of the frog 3. The second arm of the bell crank lever 9 has loosely connected therewith a rod 10 that is secured to a slide 11 to which the frog switch rails 12 and 13 respectively are loosely and pivotally secured, as at 14 and 15 respectively. The pivot members 14 and 15 pass through elongated openings in the slide 11 to prevent the binding of the parts and the free swinging of the frog switch rails when the 80 bell crank levers are operated.

85 The frog switch rails or points 12 and 13 comprise each an element shaped to correspond with the head portion of an ordinary railway rail, and the guard rails 16 and 17 to the opposite sides of the frog have their head portions cut away to receive the switch rails 12 and 13. Connecting the webs at the cut away portions of the said guard rails 16 and 17 and if desired integrally 90 formed with the said guard rails is a platform 18 which is centrally channeled from its upper face, and the side flanges 19 thus provided are beveled inwardly to receive the bent edges 20 upon the sides of the 100 slide 11.

The webs of the rails upon which the frog switch rails or points 12 and 13 rest have lateral enlargements or bosses to more effectively support the pivots 21 for the said 105 frog switch rails. These enlargements or bosses 20 may be integrally formed with the main rails, but preferably and as illus-

trated in Fig. 3 of the drawings the bosses are formed upon central enlargements in the outer faces of the plates 22, the said plates being secured to the webs of the rails in any 5 desired or preferred manner, as for instance, through the medium of rivets 23 passing transversely through the plates and through the webs of the rails. The pivot members 21 preferably comprise members having 10 cone-shaped heads which are received in conical depressions entering from the outer faces of the rail points 12 and 13, the shanks of the said pivot members passing through openings provided in the webs of the rails 15 to the opposite sides of the plates 22 or through the bosses when the rails are so integrally formed. The pivot members project a suitable distance below the rails and the said projecting ends of the said pivots 20 are threaded to receive bolt members 24, and the threaded ends of the pivots are provided with spaced transverse openings through which are adapted to be passed a holding element for the nuts, such as a cotter 25 pin 25. It is to be further understood that suitable bearing plates may be arranged at the pivots between switch points 12 and 13 and the webs of the rails upon which the 30 said points rest to facilitate the ready turning of the points 12 and 13.

The switch points 12 and 13 have their outer ends beveled in opposite directions whereby to engage with the opposite sides of the frog when either of the said points 35 are swung into contact engagement with the frog and also whereby to engage with the beveled ends of the rails 16 or 17 when the points 13 or 12 are swung to aline with the said rails. By this means it will be noted 40 that the movement of the switch points is limited and also that the said points will be maintained in proper alinement with the opposite sides of the frog when the device is operated to open either the main line or 45 the siding.

In instances where the base of the frog 3 projects a suitable distance outward of the point of the frog, the said base could, with slight alterations, be made to support the 50 platform 18.

From the above description, taken in connection with the accompanying drawing, the simplicity of the device, as well as the advantages thereof will, it is thought, be perfectly apparent to those skilled in the art to 55

which such invention appertains without further detailed description.

Having thus described the invention, what I claim is:

1. In combination with a railway switch 60 including a frog, the rails of the main line and siding in a line with the opposite sides of the frog having their heads, at their ends, cut away, switch points corresponding in shape to the heads of the rails pivoted at the 65 said cut away portions of the rails, a slideable member connecting the switch points, a platform supporting the slide, and operating mechanism for the slide.

2. A railway switch including a frog, the 70 rails alining with the frog and having their heads cut away at the ends of the said rails, the webs provided by the said cut away portions of the rails having a laterally extending enlargement, switch points, pivots for 75 the switch points entering the said enlargements, a platform connecting the webs at the cut away portions of the webs, a slide guided upon the platform, elements loosely connecting the switch points with the slide, and 80 operating mechanism for the slide.

3. A railway switch including a frog, the rails in a line with the sides of the frog having their heads adjacent their ends cut away, and the heads of said rails to the 85 opposite sides of the point of the frog being pivoted, the webs adjacent the opposite ends of the cut-away portions being widened, switch points received in the cut away portions of the rails and having pivots received 90 in the referred to widened portions of the webs of the rails, a platform connecting the webs, said platform being centrally channeled and the side walls of the channel being inclined, a slide having beveled edges received in the channel of the platform, said slide having elongated slots, pivot members passing through the switch points and entering the slots, said switch points having their 95 ends beveled in opposite directions, whereby to contact and aline with the frog at the ends thereof or to engage with the referred to beveled heads of the rails in accordance with the direction of throw of the said switch points, and means comprising mechanism connected with the slide for moving the same to actuate the switch points. 100

In testimony whereof I affix my signature.

GEORGE L. FORESTER.
